Application December 15, 1943, Serial No. 514,375

7 Claims. (Cl. 171—97)

1

The present invention relates to vibrator power supply systems and, more particularly, to vibrator power supply systems of novel and improved character.

At the present time vibrator systems are employed on a substantial scale for converting current derived from a source of relatively low voltage, such as a storage battery, into current having a considerably higher voltage, which may be required for the plate and biasing voltages of a radio transmitter or receiver. Generally speaking, a vibrator system comprises a step-up transformer having a primary winding with a center tap and a vibratory contact system causing current taken from the low voltage source alternately to flow through the two halves of such winding. In most cases provision is made for rectification of the high voltage alternating current output, this being accomplished in the simplest case by means of synchronous rectifying contacts arranged on the vibrator or by means of a suitable rectifier tube.

Although vibrator systems have been already developed to a high degree of reliability, serious difficulties have been experienced in providing vibrators having a long useful life. It has been found that the weakest elements of conventional vibrator systems are the contacts controlling the primary circuit. Since the vibrator is required to interrupt a circuit having a high inductance, the power contacts are subject to the possibility of severe destructive arcing. This danger is accentuated by the recent tendency of employing considerably higher battery voltages, such as 12 to 15 and 24 to 30 volts, this being the case particularly with aircraft installations. Prior remedies included the provision of heavy-duty contact discs made of special alloys, judicious design of the step-up transformer and also the insertion of suitable buffer condensers bridged across the transformer windings. None of these remedies, however, has provided a completely satisfactory solution of the outstanding problem.

It has now been discovered that the relatively short useful life of vibrator contacts was not due to steady state arcing conditions, which could be readily kept at a relatively low level, but to unusual arcing conditions encountered during the first few starting cycles of the vibrator, particularly during its first half cycle of operation. Exhaustive experiments carried out in this direction have demonstrated that the transient arcing conditions existing for a small fraction of a second during the starting of the vibrator will cause damage that may equal or even

5

greatly exceed the wear on the contacts caused by many hours of steady-state normal operation.

When the starting switch is closed to connect the battery or other low voltage direct current source to the vibrator and to the primary winding of the step-up transformer, the vibrator magnet of relatively high resistance is first energized and will initiate the swing of the vibrator reed. As soon as the reed has swung far enough to close one pair of the vibrator contacts, a low resistance circuit is established through half of the transformer winding, and current from the battery immediately begins to build up in this circuit. Since the resistance of this circuit is quite low, the rate of current increase is controlled principally by the counter EMF developed in the half transformer winding by the change of magnetic flux in the core. During steady-state operation of the vibrator the magnetic flux will be reversed in direction during each vibrator half cycle. It will be apparent, therefore, that if the system is designed so that the transformer will have a maximum flux of F_m at the end of each half cycle period, the total change in flux during a half cycle will be from $-F_m$ to $+F_m$, or $2F_m$.

It has been found, however, that altogether different conditions of flux will prevail during the starting cycles of the vibrator. Thus, during the starting half cycle, the flux at the start will be determined by the residual magnetism in the iron core of the transformer. In many cases this may amount to as much as $.8F_m$ and may be in the same direction as the initial magnetizing impulse. It will be evident therefore, that, disregarding saturation conditions of the iron core, the current which builds up through the transformer winding during the first half cycle will create a flux which may be additive to the residual magnetism of the core to produce a total flux of $2.8F_m$ in the transformer by the end of the first half cycle when the vibrator contacts open.

In practical vibrator power units, saturation of the transformer core may occur before this flux density is reached, in which case the current through the primary winding will increase to excessively high values. Therefore, at the end of the first half cycle of operation, when the first pair of vibrator contacts opens, a much higher current will be flowing in the primary winding than is attained during steady operation, and the flux will also be much greater than F_m . Of course, this condition of excessive current and excessive flux density imposes severe arcing conditions on the vibrator contacts as they open, and these unusual and transient arcing conditions cannot

55

2

be fully controlled by the buffer condensers normally connected in the circuit, without employing such large values as to involve damaging results during the steady-state operation, as well as uneconomical size and cost.

To reduce the severe arcing conditions during starting, it has already been attempted to incorporate certain changes in the design of the step-up transformer. This, however, at best provided a rather poor compromise since the efficiency of the transformer during steady operation was also greatly reduced, or the physical size greatly increased. Such expedients have not been completely successful even with relatively low operating voltages and the problem is greatly aggravated where batteries of a voltage higher than six volts are used, such as in aircraft electrical systems where voltages of 14 to 28 volts are quite common. This results from the greater ease of ionization of the air between the contacts at the higher battery voltages, thus facilitating forming of destructive arcs.

It is an object of the present invention to provide a simple and completely satisfactory solution of the outstanding problem.

It is another object of the present invention to provide a novel and improved vibrator system which is substantially free from the unusual and severe arcing conditions unavoidable in conventional vibrator systems, and which consequently makes it possible to considerably increase the useful life of the vibrator without decreasing the overall electrical efficiency of the system.

It is a further object of the present invention to provide a novel and improved vibrator circuit organization involving current limiting means restricting the maximum current during the initial cycles of vibrator operation and delayed action means for disabling such limiting means after the steady or normal operation has been reached.

The invention also contemplates the incorporation of electromagnetically retarded switching means into a vibrator circuit which automatically maintains preferred operating conditions both during the starting and the steady operation of the vibrator system and thereby permits combining extremely long useful life of the vibrator system with great electrical efficiency.

Other and further objects and advantages of the invention will be apparent from the following description taken in conjunction with the accompanying drawing, in which

Fig. 1 is a circuit diagram of a vibrator system embodying the principles of the present invention and including a retarded relay with a serially connected winding;

Fig. 2 is a similar circuit diagram of a modified vibrator system including a retarded relay with a shunt-connected winding; and

Fig. 3 shows a vibrator circuit embodying the invention and including a differential relay of a retarded type.

Referring now more particularly to Fig. 1, a preferred embodiment of the invention will be described. The circuit essentially comprises a vibratory reed 10 adapted to cooperate with a pair of relatively fixed contacts 11 and 12 connected to the ends of primary winding 13 of a step-up transformer 14. The secondary winding 15 of the transformer is grounded at its center tap and is connected to a full-wave rectifier diagrammatically shown at 16. This rectifier may be a vacuum tube or a separate set of contacts synchronously operable by reed 10. An electromagnet 17 is connected between reed 10 and one end

of primary winding 13 and is adapted to maintain the reed in vibratory motion when a source of low voltage current is connected in conventional manner between reed 10 and the center tap of primary winding 13.

Power is supplied to the vibrator system from a low voltage source through a switch 19, a serially connected choke coil 20, the winding of a retarded relay 21 and a current limiting resistance 10 22, all in series, said resistance being connected to the center tap of primary winding 13 of transformer 14. Relay 21 is preferably of the magnetically retarded type in which a delayed closing action is obtained by the provision of a short-circuit winding or of a copper slug 23 on the iron core into proximity of the winding. In some cases it is desirable to make the degree of the time delay effect adjustable, this being obtainable, for example, by adjustment of the copper slug on the 20 core. An armature 24 and a fixed contact 25 are incorporated into relay 21 and provide a normally open short-circuit path across limiting resistance 22. A condenser 26 is connected between the common point of choke coil 20 and of relay winding 21, and ground, and a similar condenser 27 is connected between the center tap of the primary winding 13 and ground. The object of these condensers is to provide with choke coil 20 and with the inductance of relay winding 21 a radio 30 frequency "hash" or interference filter to keep such interference as is generated by the vibrator circuit out of the battery circuit. A buffer condenser 28 may be connected across secondary winding 15 of the transformer, for reasons well 35 known by those skilled in the art.

From the foregoing description the operation of the vibrator system illustrated in Fig. 1 will be readily understood. Upon closing switch 19, current will flow from battery 18, through switch 40 19, choke coil 20, relay winding 21, current limiting resistance 22, the lower half of primary winding 13, vibrator coil 17 and back to battery 18. Vibrator coil 17 will be energized and will deflect reed 10 thereby closing power contact 12 and short-circuiting coil 17. Coil 17 now being de-energized, reed 10 will swing back and will close contact 11 thereby causing current to flow through the other half of the primary winding. It will be noted that current will flow alternately through 50 the two halves of the primary winding and will induce a current of relatively high voltage in the secondary winding 15 which is rectified by rectifier 16. Limiting resistance 22 being in the circuit, the current flowing through the primary 55 winding and interrupted by contacts 11 and 12 is maintained within preferred values so that excessive arcing of the contact points or discs is positively prevented.

After a predetermined time interval retarded relay 21 will attract its armature 24 which closing contact 25 will short-circuit limiting resistance 22. Thus, practically the full battery voltage becomes effective for actuating the vibrator system, if the slight voltage drop through coil 20 65 and relay winding 21 is disregarded. The retarding action of the relay is preferably adjusted to about $\frac{1}{25}$ to about $\frac{1}{10}$ of a second which is sufficient to carry out the first 10 to 20 half cycles. After this time the steady-state operating conditions are definitely established. While the amount of time delay is not critical, in some cases it is advantageous to provide for adjustment of the same for example by displacing copper slug 23 with respect to the core. In this 70 embodiment of the invention the retarded relay 75

is serially connected and its winding may be utilized as a choke coil in combination with condensers 26 and 27 and possibly with another choke coil 20 for the purpose of an interference filter.

In the modification shown in Fig. 2, the vibrator system proper is identical with that of Fig. 1 and similar reference characters have been used to denote corresponding parts. Therefore, it will not be necessary to repeat description of this part of the circuit. A current limiting resistance 32 is interposed in the power supply circuit and may be short-circuited by armature 34 and stationary contact 35 of retarded relay 31. In this case, however, the winding of relay 31 has a relatively high resistance and is voltage 15 operated by having it connected between the common point of choke coil 20 and of limiting resistance 32 and the other pole of the battery 18.

In the operation of this circuit current will flow through closed switch 19, choke coil 20, current 20 limiting resistance 32, the lower half of primary winding 13, vibrator coil 17 and back to battery 18 and during vibrations of the reed 10 current will be caused to flow alternately through the two halves of the primary winding of transformer 14. During the first 10 or 20 half cycles the current to be handled by power contacts 11 and 12 is restricted to safe values by means of current limiting resistance 32. After a predetermined length of time retarded action relay 31 30 becomes operative and will short-circuit limiting resistance 32 by armature 34 closing contact 35. Thus, the full battery voltage becomes effective for the vibrator after the initial starting period.

In this embodiment the delayed action relay is actuated by the battery voltage and consequently is independent of the load. The relay winding cannot be utilized as a choke coil and a separate choke coil 20 is necessary in combination with a condenser 26 for providing an interference or "hash" filter. While the relay 31 is drawing power from the battery throughout the operation of the vibrator system, this additional load may be maintained quite small by providing the relay with a high resistance winding.

The modified embodiment of the invention illustrated in Fig. 3 may be to some extent considered a combination of the circuits of Figs. 1 and 2. The connections of the vibrator with the step-up transformer are identical with those of the other embodiments and the corresponding parts have been denoted by similar reference characters. Relay 39, however, is of the differential type and is provided with a voltage winding 40 and with a current winding 41 so wound as to produce oppositely directed magnetic fields. The series circuit of the system includes battery 18, switch 19, choke coil 20, current coil 41 of relay 39, limiting resistance 42, the lower half of primary winding 13, vibrator coil 17 and back to battery 18. The auxiliary or parallel portion of the circuit includes battery 18, switch 19, choke coil 20, voltage coil 40 of relay 39 and back to battery 18. Armature 44 and contact 45 of relay 39 provide a normally open short-circuiting path for limiting resistance 42.

When initiating operation of the system by closing switch 19, both the voltage coil and the current coil of relay 39 will be energized. During the starting cycles the high surge current flowing through winding 41 of the relay will produce a magnetizing effect equal to or in excess of that produced by voltage winding 40 and will oppose closing of the relay contacts. When the 75

current reaches its normal operating value, the magnetic effect of the voltage coil becomes controlling and closes the relay contacts thereby short-circuiting limiting resistance 42. Thus, in this embodiment the differential effect of a voltage and of a current winding is employed to obtain a time delay or retarded operation of the relay. In many cases, however, it is desirable to supplement this delay action by the provision of a copper slug 43 or of an additional short-circuited winding on relay 39. In this embodiment one of the relay windings, current coil 41, may be also utilized as a choke coil in order to provide an interference filter together with condensers 26 and 27 and if necessary with an additional choke coil 20.

Although the present invention has been described in connection with a few preferred embodiments thereof, variations and modifications may be resorted to by those skilled in the art without departing from the principles of the invention. I consider all of these variations and modifications as within the true spirit and scope of the present invention as disclosed in the foregoing description and defined by the appended claims.

What is claimed is:

1. In combination with a vibrator power supply system having a reed bearing vibratory contacts for making and breaking the continuity of a circuit including a source of current and the primary winding of a transformer, a resistance initially interposed in said circuit to limit the current flowing therein, and a retarded relay under the effect of current flowing in said circuit for short-circuiting said resistance a predetermined time interval after starting the operation of said reed.
2. In combination with a vibrator power supply system including a transformer with a center-tapped primary winding and vibratory contacts for alternately passing current through the two halves of said winding, a current limiting resistance interposed in the circuit of said winding symmetrically and equipotentially with respect to the two halves thereof, and a time-delay relay under the effect of current supplied to said circuit for short-circuiting said resistance a predetermined time interval after starting the operation of said reed.
3. In combination with a vibrator power supply system having a reed bearing vibratory contacts for making and breaking the continuity of a circuit including a source of current and the primary winding of a transformer, a resistance initially interposed in said circuit to limit the current flowing therein, a retarded relay having a coil connected in said circuit for short-circuiting said resistance a predetermined time interval after starting the operation of said reed, and capacitor means for forming an interference filter with said coil to suppress undesirable oscillatory currents.
4. A vibrator power supply system comprising a source of electric current, a transformer having a center-tapped primary winding and an electromagnetic vibratory interrupter having a vibratory reed connected to one terminal of said source and a pair of stationary contacts alternately engaged by said vibratory contact during vibration thereof and respectively connected to the ends of said primary winding, the center of said winding being connected to the other terminal of said source, a switch in series with said source, a limiting resistance in series with said

source, a retarded relay having a coil in series with said source, and contact means operable by said relay adapted to short-circuit said resistance a predetermined time interval after said coil has been energized.

5. In combination with a vibrator power supply system having a reed bearing vibratory contacts for controlling the current flow through a circuit including a source of current and the primary winding of a transformer, a main switch and a current limiting resistance in series with said source of current, a retarded relay having a coil connected across said source after said switch adapted to be energized from the source at a voltage substantially independent from the load when said switch is closed, and contact means operable by said coil to short-circuit said resistance a predetermined time interval after said switch is closed.

6. In combination with a vibrator power supply system having a reed bearing vibratory contacts for controlling the current flow through a circuit including a source of current and the primary winding of a transformer, a main switch and a current limiting resistance in series with said source of current, a differential relay having a voltage coil connected across said source after said switch and a current coil connected in series with said source, and contact means operable by the joint effect of said coils to short-circuit said resistance, the relative magnetizing effect of said coils being so determined that during the initial starting surge the current coil is controlling to maintain said contact means inoperative and

that during normal steady operation the voltage coil is controlling to render said contact means operative.

7. In combination with a vibrator power supply having a reed bearing vibratory contacts for controlling the current flow through a circuit including a source of current and the primary winding of a transformer, a main switch and a current limiting resistance in series with said source of current, a differential relay having a voltage coil connected across said source after said switch and a current coil connected in series with said source, contact means operable by the joint effect of said coils to short-circuit said resistance, the relative magnetizing effect of said coils being so determined that during the initial starting surge the current coil is controlling to maintain said contact means inoperative and that during normal steady operation the voltage coil is controlling to render said contact means operative, and means operatively associated with said relay to delay actuation of said contact means after said coils are energized.
